UNITED STATES PATENT OFFICE

ARTHUR YANCEY, OF NEW ORLEANS, LOUISIANA, ASSIGNOR TO SQUEEZ EZY MOP CO. INC., A CORPORATION OF LOUISIANA

COMBINED MOP AND WRINGER

Application filed February 11, 1926. Serial No. 87,598.

The invention relates to improvements in mops of the type combining a mop and wringer in which a tubular mop-head is wrung when twisted around a handle upon which it is telescoped with one end fast to the end of the handle, and the other end fast to a hand-grip, revolably and slidably mounted thereon, for applying the wringing twist.

Objects of the improvement are:

10 First, to provide a mop-head which readily adjusts to tube-shape for wringing and also as well to flat or disc-shape for mopping.

Prior mop-heads of the present type were constructed of fabric formed of parallel longitudinal strands connected by perpendicularly disposed parallel, woven or stitched, cross-strands.

The prior mop-fabric readily adjusts to the tube-shape for wringing but does not so adjust just to the flat or disc-shape for mopping.

These objections are overcome by the present invention as hereinafter shown.

Second, (if desired) to provide a hip or breast counter wring (e. g. as shown at 17 in Fig. 10) enabling the operator to wring the mop-head with both of his hands on the hand-grip.

In prior mops of the present type, the operator wrung the mop with one hand only and countered the wringing force with his other hand, one hand on the hand-grip and the other hand on the handle.

Third, to facilitate removal and renewal of worn out mop-heads by providing means to eliminate the requisitely tight binding ties formerly used to permanently connect the yarn of the mop-head to the handle and hand-grip.

40 Fourth, to provide a non-abrasive and non-absorbent cap to cover the end of the mop handle which can easily be removed for detachment and renewal of the mop-head.

One form of the invention is illustrated in 45 the accompanying drawings, in which:

Fig. 1 is the view of a partly assembled mop-head.

Fig. 2 is a view of the same in section on the line 2' 2' of Fig. 1.

50 Fig. 3 is a plan view showing the mop-head

in pre-arranged assembly to mate with means for detachably connecting the yarn of the mop-head to the end of the handle.

Fig. 4 is a detail view of a section on the line 4' 4', Fig. 5.

Fig. 5 shows a section on the line 5' 5', Fig. 4.

Fig. 6 is a view in detail of a section on the line 6' 6', Fig. 7, showing means for detachably connecting the yarn of the mop-head to the hand-grip.

Fig. 7 shows a section on the line 7' 7', Fig. 6.

Fig. 8 is a section on the line 8' 8', Fig. 9, showing the mop in operation.

Fig. 9 shows a section on the line 9' 9', Fig. 8.

Fig. 10 is a view of the mop in position for wringing the mop-head.

Fig. 11 shows an enlarged section of the hip counter and mop handle as indicated by the line 11' 11', Fig. 8.

Fig. 12 shows an enlarged section of the hip counter and mop handle as indicated by the line 12' 12', Fig. 8.

Fig. 13 is a fragmentary view showing a preferred arrangement of the meshes of the netted fabric, and showing the lower end of mop stick 5 in section.

1 is a mop-head made of netted and knotted fabric, such as an ordinary fish seine, preferably made of soft absorbent yarn. The meshes are gathered together en masse, or bunched, so as to consist of a multitude of strands in thickness. The knots appear as in rows 2.

The strands or meshes at one end 3 of the mop-head are bunched, pre-arranged and secured so that when completely assembled in tube-shape (see Fig. 3) it will circumferentially mate with the serrated tip 4 (if employed) for detachably fastening the yarn of the mop-head to the end of the handle 5 (see Figs. 4 and 5). The tip 4 may be secured to the end of the handle by a pin, screw or indentation not visible in the section.

Strands at the other end of the mop-head are bunched, pre-arranged, secured and assembled and may circumferentially mate with the serrated plate 6 for detachably securing

the yarn of the mop-head to the hand-grip 7 (see Figs. 6 and 7).

The ends of the yarn mop-head may be attached to the hand grip and to the handle by any suitable fastening means.

Suitable fastenings such as studs or screws 8 may be provided to secure the serrated plate 6 to the hand-grip.

The assembly of strands may be re-inforced 10 with the cloth binding 9 and the selvage may be strengthened and stiffened by rows of cross-stitching 10 and 11.

One end of the mop-head is drawn into pre-arranged annular shape 12 and so held 15 by a fastening device, such as a cord or ring 13 (see Figs. 1, 2, and 3).

The other end of the mop-head is provided with fastening means here shown as a cord 14 which may be sufficiently long to encircle 20 the hand grip as shown (see Fig. 6) at least three times and provide for the bow knot 15.

A cap 16 of rubber or other non-abrasive material may cover the tip 4.

The pre-arranged mop-head can easily and 25 quickly be connected to the mop-stick by removing the friction cap 16, then telescoping the handle 5 with the mop-head and seating the annular end 12 on the serrated tip 4 (see Fig. 4), then tying the re-enforced selvage 30 around the hand-grip 7 and serrated plate 6 (see Fig. 6) with the cord 14 in two "simple" or "half-square" knots and one "bow knot" and then replacing the friction cap 16.

When the mop-head is being wrung, the 35 resultant longitudinal tension in the head may cause the serrations at the end of the mop handle and on the hand-grip to embed in the mop fabric and prevent slippage independently of circumferential tension in the 40 binding ties at the end of the handle and on the hand-grip.

This greatly simplifies and facilitates connection and detachment of the mop-head and mop-stick for removal of the head when it 45 needs boiling, cleaning or drying or when it is worn out and should be renewed.

The hip or breast counter wring 17 if employed consists of a lever pivoted at 18 and conveniently held as shown (see Fig. 8) when 50 not in use. This is adapted to rest on the right hip or between the left arm and breast of the operator and to counter the wringing force when both of his hands, applied to the hand-grip, are employed to wring the mop.

Owing to peculiar characteristics of netted fabric, a mop-head constructed of such material, and arranged, assembled and mounted as shown, is capable of assuming the tube-like form illustrated in Fig. 10, which is best suited for wringing the mop, and as well also the flat or disc-like shape as shown in Figs. 8 and 9, which is best suited for mopping.

By the arrangement shown herein, the netted fabric, when the hand grip is pulled 65 away from the lower end of the mop stick,

becomes a tube surrounding the handle, as shown in Fig. 10, with the stick in its center or axis. The yarns, in this position, will be all substantially parallel to the handle. When the sleeve is moved somewhat, toward the lower end of the handle, the meshes may open somewhat, forming roughly diamond-shaped openings between the meshes, the long diagonals of the diamonds being substantially parallel to the mop handle, and the short diagonals being approximately perpendicular to the handle. When the sleeve is dropped down upon the lower end of the mop handle, and the handle rotated between the hands, the mop head spreads out into substantially a double-thickness disc, (see Figs. 8 and 9) to be used for mopping the floor. In this condition the yarns or strands (each doubled once upon itself) form a disc composed of two thicknesses of the netted fabric, 75 the long diagonals of the diamonds, and also the yarns or strands themselves, being substantially radial therein.

To enable construction and use, I have described and illustrated a simple form of the invention without waiving my right to equivalent forms.

I claim:

1. A mop comprising a handle, a revolvable and longitudinally slidable sleeve thereon, a cylindrical fabric of fish-net mesh loosely fitted about said handle and attached at one end near the end of the handle and at the other to the movable sleeve, said net having the diagonals of its meshes approximately parallel and perpendicular to the mop handle when in the untwisted condition.

2. A mop head comprising a substantially cylindrical tubular fabric of fish-net mesh, adapted to be carried upon a mop handle, with the strands of said fabric all substantially parallel to the said handle when said mop head is stretched tightly without twisting.

ARTHUR YANCEY.
